DESIGN FOR A COMBINED BOTTLE AND STOPPER

Eula Manes Stone, New York, N. Y., assignor to Prince Matchabelli, Inc., a corporation of New York

Application May 11, 1937, Serial No. 69,289

Term of patent 14 years

To all whom it may concern:

Be it known that I, Eula Manes Stone, a citizen of the United States and a resident of the city, county, and State of New York, have invented a new, original, and ornamental Design for a Combined Bottle and Stopper, of which the following is a specification, reference being had to the accompanying drawing, forming part thereof.

bined bottle and stopper showing my new design;

I claim:

An ornamental design for a combined bottle and stopper as shown.

EULA MANES STONE.
